(62) Division of application No. 29/740,580, filed on Jul.
6, 2020, now Pat. No. Des. 922,569, which is a
division of application No. 29/655,861, filed on Jul. 9,
2018, now Pat. No. Des. 892,316, which is a division
of application No. 29/580,007, filed on Oct. 5, 2016,
now Pat. No. Des. 825,743.

(57) **CLAIM**

(51) **LOC (13) Cl. 24-04**
(52) **U.S. Cl.**
USPC **D24/124**

The ornamental design for an absorbent article, as shown
and described.

(58) **Field of Classification Search**
USPC D24/124, 125, 126, 189, 190, 191, 192;
604/347, 348, 354, 358-361, 378, 385.01,
604/385.201, 385.22, 385.24, 385.25
CPC A61F 13/15; A61F 13/64; A61F 13/476;
A61F 13/5611; A61F 13/4704

DESCRIPTION

See application file for complete search history.

(56) **References Cited**

FIG. 1 is a perspective view of an embodiment of an
absorbent article showing our new design;
FIG. 2 is a front view of the absorbent article of FIG. 1;
FIG. 3 is a right side view of the absorbent article of FIG.
1;

U.S. PATENT DOCUMENTS

FIG. 4 is a back view of the absorbent article of FIG. 1;
FIG. 5 is a left side view of the absorbent article of FIG. 1;
FIG. 6 is a top view of the absorbent article of FIG. 1; and,
FIG. 7 is a bottom view of the absorbent article of FIG. 1.
The broken lines shown in FIGS. 1-7 illustrate portions of
the absorbent article that form no part of the claimed design.
